By his Attorney Phillips Abbott

UNITED STATES PATENT OFFICE.

MAX E. PESTER, OF GLEN COVE, NEW YORK.

SUBMARINE STRUCTURE.

No. 845,813.

Specification of Letters Patent.

Patented March 5, 1907.

Application filed December 7, 1906. Serial No. 346,759.

To all whom it may concern:

Be it known that I, MAX E. PESTER, a citizen of the United States, and a resident of Glen Cove, Nassau county, Long Island, 5 State of New York, have invented a new and useful Improvement in Submarine Structures, such as submarine boats, caissons, and the like, of which the following is a specification, reference being had to the accompanying drawing, which illustrates a view, partly in section, of a submarine boat embodying the invention.

No attempt has been made to show in the drawing the correct construction of a submarine boat, because the invention is, as stated above, equally well adapted to use in connection with any submerged structure inclosing a space in which human beings may be imprisoned, deprived of air, and sometimes of food and water as well; but since the invention is well adapted to use in connection with submarine boats the general outlines of such a structure have been used in the drawing to illustrate one application 25 of the invention.

A represents the hull of the vessel, caisson, or similar structure.

B B are two water-tight casings set in the upper part, deck, or shell C of the structure. 30 They are closed by suitable heavily-hinged lids D D. The casings are provided with shoulders E, upon which are water-tight gaskets or packings F. The hinges G of the lids are made strong and heavy, and opposite them are bolts H, which are undercut or beveled at their front ends, as shown, and are supported in and adapted to slide through heavy metallic loop-like devices I, which are firmly bolted or otherwise secured to the 35 structure. The rear ends of the bolts are provided with strong upwardly-projecting lugs J. The construction of the lids and hinges and the thickness of the gaskets are such that when the lids are forcibly pressed 40 down the gaskets will be put under water-tight compression, and so held by the bolts when their forward beveled ends are forced over the edge of the lids.

K K are two tubes threaded at their upper 45 ends and there supported by the bottoms of the casings and near their lower ends by a suitable framing, (indicated at L.) Each tube is furnished with a water-tight gate M, which is opened and closed by a rack and 50 pinion N O, actuated by a rod P, and hand-wheel Q, the latter being located beneath the

lid, one in each of the casings. These rods are each provided with a water-tight packing or stuffing box Q', set in the bottom of the casings, respectively. A ratchet-wheel 60 R is fast on each of the rods P and is provided with a pawl S, which being engaged with the detents of the ratchet will prevent the turning of the rods P, thus securely holding the gates M closed and open as the case may be. 65

The operation is as follows: If the submarine vessel when submerged should for any reason be unable to come to the surface, or if because of accident or the failure of the usual apparatus to work, or for any other reason 70 the men in a caisson or similar structure should become imprisoned therein without supply of air, food, or water, then the men could be relieved and their lives saved as follows: A submarine diver, taking with him 75 the ends of two suitable pieces of pipe or hose provided with suitable couplings and a hammer, descends upon the structure and with the hammer knocks back the bolts H H by striking against the studs J J. This releases 80 the lids D D, which are then lifted. Thereupon the two pieces of pipe or hose are coupled to the exposed upper ends of the tubes K K, and then the pawls S being disengaged from the ratchet-wheels R the hand-wheels 85 Q are operated in such manner as to open the gates M M, thus establishing an inlet and an outlet connection between the interior of the structure, whatever it may be, and the open air above. Thereupon fresh air, food, and 90 water, the two latter being preferably inclosed in suitable packages or receptacles, may be supplied through the tubes and free fresh air circulation established through them. 95

The stated tubular connections may be established and broken as often as desired or maintained until plans can be put into execution for the release of the imprisoned men.

It will be obvious to those who are familiar with this subject that many alterations may be made in the mechanical details of the apparatus and yet all essential features of the invention be employed. I therefore do not limit myself to the details as shown. 100

I claim—

1. In a structure of the class stated, recesses made in the outer surface thereof, water-tight lids adapted to close the outer side of the recesses, a pair of tubes extending from the interior of the structure to and into the recesses, means whereby pipes or hose 110

may be connected with the outer ends of the tubes within the recesses, gates constructed and arranged to open and to close the tubes and means located within the recesses for actuating the gates.

2. In a structure of the class stated, recesses made in the outer surface thereof, water-tight lids adapted to close the outer side of the recesses, a pair of tubes extending from the interior of the structure to and into the recesses, means whereby pipes or hose may be connected with the outer ends of the

tubes within the recesses, gates constructed and arranged to open and close the tubes, means located within the recesses for actuating the gates and means to lock the gates in their open and closed positions.

In testimony whereof I have signed my name to this specification in the presence of two subscribing witnesses.

MAX E. PESTER.
